UNITED STATES PATENT OFFICE

DAVID A. GRAY, OF CHATTANOOGA, TENNESSEE

ROTARY ENGINE

Application filed September 4, 1930. Serial No. 479,770.

This invention relates to improvements in rotary engines, and it consists of the constructions, combinations and arrangements herein described and claimed.

5 An object of the invention is to provide a rotary engine which is equipped with sealing joints between the continuously revolute abutment plate and the oscillatory piston plate for the purpose of preventing the leakage of fluid past the important joints between these members.

Another object of the invention is to provide an oscillatory piston plate which accurately fits the globular working chamber 15 of the engine, and is continuous with the exception of diametrically opposite recesses in which the sealing joint members are fitted and also in which the sealing joint members serve to connect the inclined or oblique abutment plate so that the latter is made to revolve continuously while the piston plate oscillates.

Other objects and advantages will appear in the following specification, reference being had to the accompanying drawings in which:—

Figure 1 is a side elevation of the improved engine.

Figure 2 is a vertical section taken on the 30 line 2—2 of Figure 1.

Figure 3 is a vertical longitudinal section of the engine.

Figure 4 is a detail perspective view illustrating the assemblage of the piston and 35 abutment plates by means of the sealing joints.

Figure 5 is a detail edge view of the piston plate, particularly illustrating how one of the sealing joints is assembled in the corresponding recess of said plate.

Figure 6 is a perspective view of the sealing joint knuckle, the structure being shown as though viewed on the line 5—5 of Figure 3.

Figure 7 is a horizontal section taken on the line 7—7 of Figure 3.

Figure 8 is a detail view of the shaft.

Figure 9 is a section taken substantially 50 on the line 8—9 of Figure 7, particularly

illustrating the medial ball construction of the shaft.

Figure 10 is a detail sectional view showing how one of the halves of the ball is combined with the shaft.

This invention is an improvement on the engine patented by David A. Gray, December 29, 1931, #1,839,147. The instant invention is a simplification of that engine, certain novel structural features being looked to as rendering the device more favorable for some purposes. In addition to these features an outstanding characteristic resides in certain sealing joints which not only produce a leak-proof joint between the piston and abutment plate but also cause the latter to rotate so that the possibility of wearing the latter unevenly is totally eliminated.

With these general statements in mind attention is directed to the drawings. A base 1 of any suitable description supports a casing 2 which defines a globular working chamber 3. The casing is made in halves (Figs. 1 and 3), to enable the assemblage therewithin of an abutment plate 4 (Fig. 3) and piston plate 5 as well as the various components of a shaft 6.

For the purpose of this assemblage the halves of the casing 2 are flanged at 7. Bolts 8 secure the halves together. Each casing half has a sleeve 9. These sleeves are in axial alignment and constitute a bearing for the shaft. Glands 10 of any known order, compress the packings 11 in the known manner.

The lowermost half of the casing 2 as well as the sleeve 9 at the right (Fig. 3) are each a part of the base 1. The uppermost half of the casing is in the nature of a cover, being made separate from the base. When these parts are assembled the globular casing 2 will be completed.

At the right end of the shaft 6 there is an oil reservoir 12 (Fig. 3) which is held down to any appropriate support by fastening means that are passed through its flanges 13 (Fig. 1). The right end of the shaft 6 extends into and turns in the reservoir, there being a duplicate gland 14 and its packing to prevent the escape of oil. Oil is delivered to the reservoir under pressure through a line 15.

pipe 15 and thence conducted to the internal working parts of the engine by way of a passage 16 running lengthwise of the shaft 6. Laterals 17 (Fig. 3) conduct some of the oil from the passage 16 to the bearing surfaces of the sleeves 9. The presence of the oil passage 16 makes it possible to virtually operate the piston plate 5 in a body of oil by virtue of the passage extending beyond the sides of the plate (Fig. 7) as presently brought out.

A channel 18, which is the composite of identical annular rabbets on the inner edges of the casing halves (Fig. 3), receives what might be known as the rim of the abutment plate 4. This plate consists of a ring which extends to a ball 19 that forms part of the shaft 6 (Fig. 2). The abutment plate has a round central hole 20 (Fig. 4) to receive the ball. The abutment plate revolves around the ball while the ball revolves inside of the hole 20.

The piston plate 5 is a complete disc with the exception of recesses 21 (Figs. 3 and 5) that are cut in from the edges as far as the periphery of the ball 19 at diametrically opposite points (Fig. 3). It is through certain sealing joints that the plate 4 is connected with the plate 5, the effect of the connection upon revolution of the shaft 6 being an oscillation of the piston plate 5 and a continuous rotation of the abutment plate 4.

Each sealing joint comprises a knuckle 22 (Figs. 4 and 5). This is nothing more than a cylindrical plug which is made concave at 23 on its inner end and convex at 24 at its outer end to agree with the contours of the ball 19 and the working chamber 3 with which each knuckle has a close but working fit. Parallel longitudinal slots 25 on diametrically opposite sides of each knuckle 22 receive the fins or wings 26 (Fig. 5) to which the portions of the plate 5 are reduced immediately adjacent to each recess 21.

There is a snug fit between the slots 25 and fins 26. The knuckles 22 will always assume the same relationship to the piston plate 5 although these knuckles are constantly changing in radial relationship to the shaft 6 during rotation. The central hole 20 of the abutment plate has slot extensions 20^a (Figs. 4 and 5) to receive the knuckles 22, the parallel walls of the slot extensions being concaved (Fig. 5) to suit the contour of the knuckles 22.

Studs 27 secure the knuckles 22 of the sealing joints to the abutment plate 4. These studs are simply carried by the knuckles and are extended far enough into the abutment plate to effect the connection. It is by means of the extensions of these studs into the rim of the abutment plate (Fig. 3) that the latter is made to rotate.

The ball 19 is made in two parts. Each section 28, 29 has an annular rib 30 which

fits in a corresponding groove 31 on the respective side of the piston plate 5 (Fig. 9). The piston plate thus virtually occupies a slot in the ball, the sections 28, 29 of the latter being sufficiently less than half spheres to accommodate the plate 5 therebetween and yet compose a complete sphere when assembled on each side of the piston plate.

The slot in the ball 19 has an extension 32 (Fig. 4) in the shaft 6. It has been stated that the piston plate 5 oscillates. The oscillation occurs on an appropriate pivotal member 33 which also constitutes the connector for the ball sections 28, 29. The member 33 is sufficiently narrow so as not to obstruct the passage 16. Oil can thus flow past each side of the plate 5 and enable the latter to oscillate through a volume of oil to insure its lubrication.

By preference the ball 19 is made of metal dissimilar from that of the shaft 6. For example, the ball will be made of cast iron while the shaft will be made from steel. The shaft 6 has a separable side 34 which when secured at 35 (Fig. 7) completes the shaft. It is to the chief component of the shaft 6 and its side 34 that the ball sections 28, 29 are secured in any appropriate way. Should there ever be any evidence of wear on the surface of either ball section it would be a comparatively easy and cheap operation to replace that section rather than to substitute an entirely new shaft.

The abutment plate 4 divides the working chamber 3 so that the casing 2 actually contains two working chambers. Each of these has intake and exhaust openings 36, 37 and 38, 39 respectively on the left and right sides as well illustrated in Figure 1. Provisions against the leakage of fluid around the abutment and piston plates 4, 5 comprise piston rings 40, 41 set in the outer and inner edges of the abutment plate (Fig. 2), packings 42 set in the flanges 7 beside the abutment plate and a piston ring 43 set in the peripheral edge of the piston plate 5.

The operation is readily understood. Consider Figure 3. The construction is shown as it would appear to an observer standing in front of Figure 1, but the view is a vertical section showing the inner parts. The piston plate 5 is in the upright position and is being driven away from the observer (in the direction of arrow 44, Fig. 2) by virtue of fluid being admitted at the previously uncovered intake opening 36. The pressure against the face of the plate 5 causes the shaft 6 to rotate.

As the shaft rotates, the sealing joints, exemplified by the knuckles 22 (Fig. 3), will cause the abutment plate 4 to rotate also, this by virtue of the connection of the knuckles with both plates 5, 4. The turning of the abutment plate results in a continuous changing of the bearing surfaces so that any

wear will be uniform throughout. As revolution of the shaft continues the piston plate 5 will partake of an oscillatory or rocking motion on its pivotal member 33 by virtue of 5 being forced to follow the inclined or oblique abutment plate.

There is a continual opening and closing of the ports, and the result is a rapid rotation of the shaft 6. One of the principal purposes 10 of the construction is to prevent the escape of active pressure fluid past the joint between the abutment plate 4 and piston plate 5 into the exhaust side of the working chamber. This is accomplished by the sealing 15 joints which not only insure the utmost freedom of movement between the parts but also act as a seal against the escape of fluid in either direction.

While the construction and arrangement 20 of the improved engine is that of a generally preferred form, obviously modifications and changes may be made without departing from the spirit of the invention or the scope of the claims.

25 I claim:—

1. An engine comprising a casing having a working chamber, rotatable abutment means, an oscillatory piston plate, a shaft carrying the piston plate for revolution by 30 force of pressure fluid in the working chamber exerted against said plate, and combined joint and fluid seal means connecting the piston plate with the abutment means, causing the abutment means to rotate and compensating for the resulting oscillation of the 35 piston plate.

2. In an engine having a casing with a working chamber, a piston plate operable in the chamber, a shaft by which said plate is 40 rockably carried, and abutment means with which said plate coacts being located obliquely across the chamber in reference to the shaft; means constituting sealing joints connecting the abutment means with the piston plate, causing rocking of the latter and rotation of the abutment means during shaft rotation, and means effecting a fluid seal at the points of connection of the piston plate with said universal joint means.

45 3. An engine comprising a casing having a globular working chamber, a shaft supported by the casing having a ball situated medially of the chamber, a piston plate fitting the chamber, being carried by the shaft and revoluble in the chamber by force of pressure fluid exerted thereagainst to rotate the shaft, said plate having diametrically opposite recesses, abutment means carried by the 50 casing and extending into the chamber to bear on the ball, said means being situated obliquely to the shaft, and sealing joints connecting the plate with the abutment means comprising knuckles fitted in the recesses and studs connecting the knuckles with the 55 abutment means to cause the latter to rotate.

4. An engine comprising a casing having a globular working chamber, an abutment plate revolvably carried by the casing, extending into the working chamber and having a central hole, a shaft journaled on the casing 70 having a ball located medially of the chamber and fitting the hole, a piston plate carried by the shaft, fitting the working chamber, said plate having diametrically opposite recesses extending from points approximately flush with the ball to the wall of the working chamber, knuckles occupying the recesses and having slots to receive the edges of the recesses to perfect a fluid seal between the sides of the piston plate, and means connecting the 75 knuckles with the abutment plate causing revolution of the latter upon rotation of the shaft by force of fluid pressure exerted against the piston plate.

5. In an engine comprising a casing having a working chamber, a shaft journaled on the casing having a ball located medially of the working chamber there being a slot in the shaft and ball, a piston plate in the slot and fitting the working chamber, means by which 80 said plate is pivoted to the ball, an abutment plate revolvably mounted on the casing and extending into the working chamber to define a partition, said plate having a hole in which the ball fits, and means providing both 85 a joint between the piston and abutment plates and a seal to prevent the escape of fluid from one side of the partition to the other.

6. In an engine, a piston plate, and a shaft 100 which is slotted to movably receive the plate, said shaft having an oil passage exceeding the plate in width to continuously conduct oil along the sides of the plate.

7. In an engine, a piston plate having 105 annular grooves on opposite sides, a shaft which is slotted to rockably receive said plate, and a ball incorporated in the shaft through which the slot also extends, said ball having 110 annular ribs fitting in the grooves.

8. In an engine, a shaft, a separable side, said shaft and side having a slot, a piston plate rockable in the slot, and a ball comprising half sections incorporated in the respective shaft and separable side, said sections 115 being sufficiently less than half spheres to constitute a continuation of the slot.
